UNITED STATES PATENT OFFICE.

FRED A. CONRAD, OF MILWAUKEE, WISCONSIN, ASSIGNOR TO AMERICAN LACE PAPER CO., OF MILWAUKEE, WISCONSIN.

DESIGN FOR A PAPER NAPKIN.

Application filed January 24, 1927. Serial No. 20,483. Term of patent 14 years.

To all whom it may concern:

Be it known that I, FRED A. CONRAD, a citizen of the United States, residing at Milwaukee, in the county of Milwaukee and State of Wisconsin, have invented a new, original, and ornamental Design for Paper Napkins, of which the following is a specification, reference being had to the accompanying drawings, forming part thereof.

Figure 1 is a plan view of a paper napkin of linen-like appearance and ornamental border, thereby showing my new design.

Figure 2 is an enlarged plan view of one corner.

Fig. 3 is a section substantially on the line 3—3 of Fig. 2.

I claim:

The ornamental design for a paper napkin as shown.

FRED A. CONRAD.
